UNITED STATES PATENT OFFICE.

HERMAN L. GREVE, OF BROOKLYN, NEW YORK.

MAILING RECEPTACLE.

Application filed June 26, 1924. Serial No. 722,460.

To all whom it may concern:

Be it known that HERMAN L. GREVE, a citizen of United States, residing at 357 Macon St., Brooklyn, New York, has invented a new and useful Improvement in Mailing Receptacles, of which the following is a specification.

My invention relates to mailing receptacles.

10 The object of my invention is to provide an improved receptacle and improved means for fastening the flaps of a mailing receptacle to the body portion thereof in such a manner as to eliminate a number of troublesome features inherent in fastening means for this purpose heretofore in use.

15 A further object is to provide a device of this character which will require a minimum of time to lock and unlock after the 20 contents of the wrapper have been placed therein.

25 The locking means heretofore employed for the purpose of holding the flaps of the receptacle in locked position, extend above the plane surface of the flap and their edge portions present side abutments, due to the thickness of the material of which the locking element is made, and the embossing thereon, which often extends above the 30 surface of the flap a considerable distance.

35 The parts thus extending catch in other mail matter in transit which results in injury to such matter and also often nips the locking means loose from the wrapper.

40 To overcome this trouble I have provided a locking means, hereinafter referred to as a clip, which has but one part to bend in locking the wrapper, and which presents no abutment portion which can catch in other 45 mail matter in transit.

Referring to the drawings which form a part of this specification,

Fig. 1 is a plan view of a mailing receptacle of rectangular form, and disclosing 45 my improved clip thereon in locked engagement with the flap of the wrapper.

Fig. 2 is a plan view of a portion of a receptacle showing a clip in unlocked relation to the flap.

50 Fig. 3 is a longitudinal sectional view of a portion of the receptacle and clip showing the clip in unlocked position, and

Fig. 4 is a similar view showing the clip in locked position.

55 Fig. 5 is an inverted plan view of the clip.

Fig. 6 is an edge view of the clip.

Fig. 7 is a cross sectional view in line X—X of Figure 5.

A, indicates the receptacle made of stiff paper stock. A¹ indicates the upper flap portion thereof, and A² the lower flap portion which overlies the body portion A, as illustrated in Figure 1.

The flap portions are provided with openings B—B respectively located near the ends 65 of the receptacle as shown, and preferably formed with circular edges B¹, each flap having a rectangular shaped recess C—C respectively in which the shank portion D¹ of the clip D rests when the clip is bent in 70 locked relation with the wrapper as illustrated in Figures 1-3 and 4.

The wrapper is folded as shown in Figure 1, the end flap portions E—E respectively, being first turned in as shown after 75 the contents are placed in the wrapper, then the upper flaps A¹ and A² are folded so as to overlap each other, crossing at the point F as indicated in dotted and full lines.

The clips D—D respectively are preferably made of thin copper having no spring quality, and are permanently fastened to the end flaps E by tangs G—G etc. as shown and rest below the openings B as shown in Figures 2 and 3, and the shank D¹ is bent 80 as the clip is forced into locked position as shown in Figures 1 and 4, the shank portion D¹ resting in the recessed portion C of the receptacle, thus preventing any relative shifting of the flap portions of the receptacle. The button shaped end of the clip is pressed to provide a dome shaped end the outer circular edge of which is shaped and rests in close contact with the surface of the flap as illustrated at H in Figure 7 thus presenting no edge or abutment wall that will catch in other mail matter in transit. It will also be observed that the shank portion is covered and protected by the side 90 walls of the flap portion.

In fastening large quantities of these receptacles, a considerable amount of time is saved over that required for other similar mailing receptacles and a package is provided that overcomes the troubles above set forth.

Having thus described my invention I claim as new—

1. A mailing receptacle comprising a flap portion having an opening with a recess formed in one side thereof; a clip fastened to the receptacle and having a shank which 110

fits and rests in said recess when the receptacle is locked, and also having a dome shaped end formed integral with said shank, the exposed edge of which rests on 5 the surface of said flap.

2. In a mailing receptacle, a bendable clip having a shank fastened to the receptacle, and a closure flap for the receptacle having an opening through which said clip 10 may be lifted and bent for locking the flap closed, said opening having an offset recess to fit the shank when said clip is in its effective bent position.

3. In combination, a container having a

closure flap, a clip comprising means for 15 securing the clip to the container and having a shank extending therefrom with a single rigid head formed integral therewith at the free end of said clip, the closure flap for said container having an opening provided with an offset recess adapted to fit the shank, said shank being bendable within 20 said recess so that said head overlies the securing means to lock the flap.

In testimony whereof, I have signed my 25 name to this specification this 10th day of June 1924.

HERMAN L. GREVE.
